UNITED STATES PATENT OFFICE.

MARTIN LAERNOES AND JOHN DUNN, OF STREATOR, ILLINOIS, ASSIGNORS
TO THE VULCAN DETINNING COMPANY, OF NEW YORK, N. Y., A COR-
PORATION OF NEW JERSEY.

APPARATUS FOR TRANSFERRING DETINNED SCRAPS.

SPECIFICATION forming part of Letters Patent No. 737,117, dated August 25, 1903.

Application filed November 26, 1902. Serial No. 132,719. (No model.)

To all whom it may concern:

Be it known that we, MARTIN LAERNOES, a citizen of the Kingdom of the Netherlands, and JOHN DUNN, a citizen of the United States 5 of America, both residing in Streator, in the county of LaSalle and State of Illinois, have invented certain new and useful Improvements in Apparatus for Transferring Detinnted Scraps, of which the following is a 10 specification.

This invention relates to an improved apparatus for transferring detinnted scraps by taking the same from the trucks coming from the detinning-vats into the washing-tank and 15 removing thereby the adhering detinning solution, the apparatus permitting the transferring and lowering of any number of baskets in a group and in vertical position, so as to facilitate thereby the handling of the 20 baskets and produce considerable saving of time in placing them into the washing-tanks and transferring them from the same again to the trucks; and for this purpose the invention consists of an apparatus for transferring 25 detinnted tin-scrap which comprises a movable carriage supported on ways, a suspension-bar provided with a number of hooks each adapted to engage the bails or handles of two adjacent baskets at the same time, 30 means for counterbalancing said suspension-bar and basket for lifting or lowering the same into the tanks, transferring the same to the truck, and vice versa.

The invention consists, further, of the special construction of the suspension-bar and hooks for taking hold of a plurality of baskets at the same time and handling them for submerging in the washing-tank or placing on the trucks, as the case may be, which will 40 be fully described hereinafter and finally pointed out in the claims.

In the accompanying drawings, Figure 1 represents a side elevation of the improved apparatus for transferring detinnted scraps, 45 showing the basket in position on the truck before being transferred into the washing-tank. Fig. 2 is a similar elevation showing the baskets transferred by the improved ap-

paratus into the washing-tank. Fig. 3 is a plan view of Fig. 1. Fig. 4 is a vertical trans- 50 verse section on line 4-4, Fig. 1, drawn on a larger scale; and Fig. 5 is a perspective view of the suspension-bar with its basket-holding hooks.

Similar letters of reference indicate corresponding parts.

Referring to drawings, A represents a suspension-bar which is made of iron or steel of sufficient thickness and provided with a number of hooks a, the flattened shanks of 60 which are attached thereto by rivets or otherwise and which extend in forward direction at right angles to the bar, being bent in such shape that each hook readily engages the supporting handles or bails of two adjacent detinning-baskets, such as are employed in the process of detinning tin scraps or clippings by the electrolytic process. The suspension-bar A is suspended, by means of straps S, from a sheave or pulley B, over which is placed a 65 wire rope C, said wire rope being conducted over sheaves d of a carriage D, which is moved in horizontal ways E, that are supported in suitable posts, brackets, hangers, or otherwise in proper relative position to the trucks 70 and tanks over which the baskets are to be transferred. One end of the wire rope is connected with a weighted plunger. The plunger is guided in a hydraulic, steam, or air cylinder F, to which the pressure medium is admitted by a suitable valve-gear operated by the attendant. The opposite end of the wire 75 rope is attached to a stationary point or abutment L on the end of the guideways E for the carriage D. The frame of the carriage 80 D is provided with inclined downwardly-extending handles D', which are arranged symmetrically and at opposite sides of the suspension-bar A and sheaves B, said handles serving for the purpose of moving the carriage, 85 with the suspension-bar and baskets suspended therefrom, from the truck to the tank, then from the tank to the transferring-truck after the washing operation has been completed. The track for the transferring-truck T runs 90 alongside all the washing-tanks, only one of

95

which, V, is shown in the drawings, in connection with similar transferring apparatus, extending above and across all tanks in the same manner as the transferring apparatus 5 in Fig. 2 extends across the washing-tank. A plurality of baskets, preferably eight, containing the detinned scraps is submerged in the tank, so as to clean the detinned scraps from all adhering solution after the process 10 of detinning is completed. The eight baskets are simultaneously taken hold of and transferred from the trucks by the hooks of the suspension-bar A, each hook engaging the supporting handles or bails of two adjacent 15 baskets G, as shown in Fig. 1, which being taken hold of at one side of their center of gravity are suspended vertically adjacent to each other from the suspension-hooks of said bar, as shown in Fig. 4. Thus lifted by the 20 suspension-hooks they are transferred, by means of the carriage and ways, into position vertically above the washing-tank and then lowered, so as to be submerged in the same. By the dipping or submerging of the baskets 25 with the scrap into the tank the adhering solution is removed from the same, after which the baskets are lifted again by reversing the valve-gear of the hydraulic, air, or steam operating cylinder by the attendant, so that the 30 baskets are lifted out of the tank and returned again by taking hold of the handles back to the truck-platform, which then conveys the baskets with the scraps to the place where the scraps are compressed into blocks 35 ready for being returned to the mill for being melted.

By the apparatus described a plurality of pairs of baskets can be simultaneously transferred from the trucks to the washing-tanks 40 and from the washing-tanks to the place where the scraps are removed from the baskets for being compressed, the transferring apparatus having the advantage that the baskets are always suspended by their own gravity in vertical position, so that the handling 45 of single baskets is dispensed with and considerable time and labor in transferring and washing the scraps is saved.

Having thus described our invention, we claim as new and desire to secure by Letters 50 Patent—

1. An apparatus for transferring detinned scraps, which consists of stationary guideways, a carriage provided with handles supported on the same, sheaves on said carriage, 55 a wire rope passing over said sheaves, a guide-sheave suspended on said rope between the sheaves of the carriage, a suspension-bar carried by said guide-sheave, a plurality of hooks attached to said bar, said hooks being adapted 60 to engage the adjacent bails of a plurality of baskets containing detinned scraps, and means for raising or lowering the suspension-bar, substantially as set forth.

2. An apparatus for transferring detinned 65 scraps, consisting of stationary horizontal guideways, a carriage provided with sheaves moving on said guideways, handles extending downwardly from said carriage, a wire rope attached to a stationary point at one end and 70 passing over the sheaves of the carriage, a guide-sheave on said rope between the sheaves of the carriage, a suspension-bar located on the guide-sheave, said bar being provided with a plurality of hooks for engaging the 75 bails of the scrap-containing baskets, and means connected with the opposite end of the wire rope for raising or lowering said suspension-bar, substantially as set forth.

3. In an apparatus for transferring detin- 80 ning-baskets, a suspension-bar provided with a plurality of forwardly-extending hooks having flattened shanks attached to said bar and extending at right angles to the bar so that each hook is adapted to engage the bails of 85 two adjacent baskets at the same time, substantially as set forth.

In testimony that we claim the foregoing as our invention we have signed our names in presence of two subscribing witnesses.

MARTIN LAERNOES.
JOHN DUNN.
